TROLLEY-RETRIEVER.

1,026,955.

Specification of Letters Patent.

Patented May 21, 1912.

Application filed April 17, 1911. Serial No. 621,642.

To all whom it may concern:

Be it known that I, SAMUEL P. KAY, a citizen of the United States, and resident of Rochester, in the county of Monroe and State of New York, have invented certain new and useful Improvements in Trolley-Retrievers, of which the following is a specification.

This invention relates to a device by which the trolley-pole of an electric car may be retrieved, or drawn down, automatically in case the trolley-wheel becomes accidentally dislodged from the trolley-wire or conductor.

The object of the invention is to produce a device of the kind in question which is simple and compact, being adapted to be mounted on the ordinary trolley-arm support without substantial alteration therein.

The invention consists in the trolley-retriever hereinafter described, as it is defined in the succeeding claims.

In the accompanying drawings: Figure 1 is a side-elevation of a trolley and a retriever embodying the present invention; Fig. 2 is a vertical section, on a larger scale, on the line 2—2 in Fig. 5, of the retriever-mechanism in normal position; Fig. 3 is a similar view showing the retriever in action; Fig. 4 is a similar view illustrating the operation of resetting the retriever; Fig. 5 is a section on the line 5—5 in Fig. 2; Fig. 6 is a section on the line 6—6 in Fig. 3; and Fig. 7 is a detail view of one of the detents by which the retriever-mechanism is normally retained against operation.

The invention is illustrated as applied to a trolley of the form commonly employed on electric street-railways. The trolley-arm 10 carries the usual trolley-wheel 11, which engages the trolley-wire or conductor 12. The lower end of the arm is pivoted, at 13, in a bracket 14 rising from the base-plate 15, and the base-plate is mounted, by the usual swivel-joint 16, upon the top of the car. The trolley-arm and wheel are supported normally by a supporting-spring 17, of which one end engages a lug 18 on the bracket 14. The other end of the spring 17 engages a head 19, fixed to a rod 20 which passes loosely through the lug 18 and is pivoted to a lug 21 on the trolley-arm. The head 19 is guided upon rods 22 projecting from the bracket 14.

The mechanism so far described is, or may be, of any ordinary or suitable construction. The novel retriever-mechanism is mounted in and upon two curved uprights 23 and 24, mounted upon the base-plate 15 and projecting upwardly on either side of the vertical plane of movement of the trolley-arm. These uprights are hollow, and their upper portions constitute guides for a saddle-shaped member hereinafter designated as the "retriever-slide". This member comprises plates 25, which slide within the uprights and have narrow portions extending through slots in the sides of the uprights. Arms 26 project upwardly from the plates between the uprights, and the arms are connected, at the top, by a cross-piece 27, which constitutes an abutment adapted to engage the trolley-arm when the retriever-mechanism operates.

The retriever-slide is actuated by two coiled springs 28 mounted in the upper extremities of the uprights. These springs are inserted through the upper ends of the uprights, and are held in place by caps 29 screwed upon said ends. In the normal position of the parts the retriever-springs 28 are compressed, the retriever-slide being retained in uppermost position by means of two detents 30, which are pivoted upon the slide, and which are held in engagement with shoulders 31 on the uprights, as shown particularly in Figs. 5 and 7, by means of springs 32. So long as the trolley-wheel remains upon the trolley-wire the parts remain in the position just described, but in case the wheel accidentally slips from the wire, the supporting-spring 17 immediately raises the arm above normal position, as illustrated by the broken line 34 in Fig. 1. By this movement the arm is brought into engagement with trip-fingers 33 projecting inwardly from the detents 30, and the arm thus rocks the detents out of engagement with the shoulders 31, and releases the retriever-slide. The slide immediately descends, through the force of the retriever-springs, and the cross-piece 27 engages and depresses the trolley-arm into a position somewhat below its normal position, as illustrated by the broken line 35 in Fig. 1. By this action the trolley-arm is prevented from engaging and injuring or breaking the cross-wires by which the conductor 12 is

supported, and the retriever-slide continues to hold the arm in depressed position until the device is reset by the conductor of the car.

5 The mechanism by which the retriever-slide is reset comprises a slide having two parallel members 36 which move in curved guide-ways on the inner surfaces of the uprights 23 and 24. The members 36 are 10 connected by a cross-piece 37, which is adapted to be engaged by the trolley-arm when the arm is sufficiently depressed. Each member 36 has rack teeth 38 formed thereon, which mesh with pinions 39 journaled upon a cross-pin 40 extending between the uprights. The pinions also mesh with racks upon a second slide, which comprises two members 41 guided upon the uprights and connected at the bottom by a 15 cross-piece 42. To reset the retriever-mechanism the conductor of the car pulls upon the cord 43 with which the trolley-arm is provided for manual operation, and thereby depresses the trolley-arm into engagement with the cross-piece 37, thus depressing the racks 36, rotating the pinions 39 and raising the racks 41. The upper ends of the latter members engage the lower ends of the retriever-slide, and thus raise 20 the retriever-slide and compress the retriever-springs until the detents are above the shoulders 31. The operator then releases the trolley-arm, which is raised by the supporting-spring 17 until the trolley-wheel again engages the conductor 12, and the parts are then in position for normal operation.

40 My invention is not limited to the details of construction and operation of the embodiment hereinbefore described and illustrated in the accompanying drawings, but may be embodied in various other forms within the nature of the invention, as it is defined in the succeeding claims.

45 I claim:—

1. In combination with a trolley-arm pivoted to move in a vertical plane, a downwardly-movable retriever-member having a portion located above the trolley-arm and adapted to engage and depress the arm when the retriever-member moves downwardly, a spring tending to move the retriever-member downwardly, and a detent by which said member is normally retained in raised position, the detent having a portion located above and in the path of movement of the arm, so as to be engaged by the arm in its upward movement and trip the detent when the arm moves above a predetermined position.

2. In combination with a trolley-arm pivoted to move in a vertical plane, a downwardly-movable retriever-member having a portion located above the trolley-arm and adapted to engage the arm directly when

the retriever-member moves downwardly, a spring tending to move the retriever-member downwardly, a detent by which said member is normally retained in raised position, the detent having a portion located above and directly in the path of movement of the arm, so as to be engaged by the arm in its upward movement and trip the detent when the arm moves above a predetermined position, and means operable by the arm, when drawn below a predetermined position, to raise and reset the retriever-member. 70

3. In combination with a trolley-arm pivoted to move in a vertical plane, an upright slide-guide fixed at the side of said plane, a retriever-slide mounted on said guide and provided with an abutment engageable with the trolley-arm when the slide is moved downwardly on the guide, a spring tending so to move the slide, and a detent for normally retaining the slide in raised position, the detent having a portion located above and in the path of vertical movement of the trolley-arm, so that the detent may be engaged and tripped by the arm to release the slide when the arm moves above a predetermined position. 80

4. In combination with a trolley-arm pivoted to move in a vertical plane, an upright slide-guide fixed at the side of said plane, 90 a retriever-slide mounted on said guide and provided with an abutment engageable with the trolley-arm when the slide is moved downwardly on the guide, a spring tending so to move the slide, a detent for normally retaining the slide in raised position, the detent being operable to release the retriever-slide when the trolley-arm moves above a predetermined position, and resetting mechanism for raising the retriever-slide to 100 normal position, said mechanism comprising a second slide mounted on said guide and downwardly-movable by engagement with the trolley-arm when the arm is drawn below a predetermined position. 110

5. In combination with a trolley-arm pivoted to move in a vertical plane, a retriever-member movable downwardly and adapted to engage the trolley-arm in such downward movement to depress the arm, a spring for so moving the retriever-member, means for retaining the retriever-member normally in operative position, said means being operable by the arm to release the retriever-member when the arm moves above 115 a predetermined position, and means for resetting the retriever-member, said means comprising a slide engageable by the trolley-arm when the arm is drawn below a predetermined position, a second slide upwardly-movable and adapted to engage and raise the retriever-member, and gearing connecting said slides whereby downward movement of the one causes upward movement of the other. 120 125

6. In combination with a trolley-arm pivoted to move in a vertical plane, two upright hollow slide-guides fixed at opposite sides of said plane, a saddle-shaped retriever-slide having its lower extremities 5 slidably movable within said guides, a spring inclosed within each guide and interposed between the corresponding end of the slide and the upper end of the guide, and a 10 detent carried by the slide and adapted to engage an abutment on one of the slide-guides, said detent having a portion engageable by the trolley-arm when the arm moves above a predetermined position so as to disengage the slide and permit it to be 15 depressed by said springs.
